UNITED STATES PATENT OFFICE.

JOHN PETER BAGAN, OF VANCOUVER, BRITISH COLUMBIA, CANADA.

GUARD AND LEDGER PLATE.

Application filed December 3, 1923. Serial No. 678,267.

To all whom it may concern:

Be it known that I, JOHN PETER BAGAN, a citizen of the United States, and resident of Vancouver, in the Province of British Columbia and Dominion of Canada, have invented certain new and useful Improvements in Guard and Ledger Plates, of which the following is a specification.

This invention relates to guards and ledger plates therefor especially adapted for use on agricultural machinery, and more particularly reaping and mowing machines.

An important object of this invention is to provide novel means whereby a ledger plate may be quickly and easily connected to a guard in such a manner that the ledger plate may be instantly detached with the aid of a simple tool, such as a screw driver.

A further object is to provide simple means whereby a ledger plate may be quickly connected to a guard in such a manner that displacement of the ledger plate as the result of pressure thereon is positively prevented.

25 A further and equally important object of the invention is to provide a ledger plate and guard which may be economically manufactured and which is durable and desirable in use.

30 Other objects and advantages will be apparent during the course of the following description.

In the accompanying drawing forming a part of this application and in which like numerals are employed to designate like parts throughout the same,

Figure 1 is a perspective of a guard equipped with the ledger plate.

Figure 2 is a longitudinal sectional view through the improved guard and ledger plate.

Figure 3 is a plan view partly in section.

Figure 4 is a perspective of the ledger plate.

45 Figure 5 is a fragmentary perspective of the guard.

In the drawing wherein for the purpose of illustration is shown a preferred embodiment of the invention the numeral 10 designates a guard, the rear portion of which is provided with an attaching member 11 by means of which the guard may be attached to a guard bar. It will be seen that the attaching portion 11 is formed with an opening 12 for the reception of a fastening

member which secures the attaching portion to the guard bar.

The invention forming the subject matter of this application resides in providing novel and simple means whereby the ledger plate 60 14 may be quickly and detachably connected to the guard without employing rivets or extraneous fastening devices as is now the custom.

With reference to Figure 3 it will be observed that the forward end of the ledger plate 14 is reduced in width to define a lip 15 and a pair of shoulders 16, the shoulders being adapted to contact with a pair of oppositely located shoulders 18 on the upper 70 portion of the guard whereby the forward movement of the ledger plate 14 is limited. Furthermore, the lip 15 is snugly received in a socket 20 formed between the shoulders 18 so that lateral movement of the ledger 75 plate with relation to the guard is positively prevented.

The forward portion of the ledger plate is formed between its longitudinal edges with a U-shaped incision 22 which defines a partly 80 severed portion which is forced or pressed downwardly to form a fastening finger 24. The terminal of the spring finger 24 is rounded and is adapted to engage beneath a bridge member 24^a spanning a cavity 26 85 formed in the guard, the bridge member 24^a being integrally formed with or suitably secured to the guard. In this manner the plate is securely and positively anchored to the guard. In preparing to securely attach the 90 ledger plate to the guard the lip 15 is inserted into the socket 20 and the rear portion of said ledger plate is forced downwardly so that the terminal of the spring finger 24 will spring past the bridge member 24^a 95 of the cavity and thereby anchor the forward portion of the ledger plate to the guard.

The rear portion of the ledger plate is provided adjacent its side edges with extensions which are bent downwardly during the stamping operation to define a pair of spring arms 30.

The spring arms 30 are adapted to be sprung over the walls 34 of vertical recesses 35 which extend entirely through the rear portion of the guard and therefore the necessity of employing cores in the manufacture or casting of this portion of the guard is overcome. It will be seen that the walls 110

or shoulders 34 are formed between their upper and lower sides with what might be said to be enlargements or projections 37 and below these projections the walls 34 incline forwardly so that when the spring arms 30 are sprung over the central enlargements 37 the ledger plate may flatly rest against the top of the guard. It might be said that the forward wall of each recess 35 is more or less V-shaped in cross section and when the spring arms 30 are sprung over the highest point of the V the ledger plate will lie flatly in contact with the adjacent surface of the guard.

In carrying out the invention the terminal portion of each spring arm 30 is extended inwardly to define a lug 39 to provide a means whereby the arms may be conveniently forced over the enlargements 37 without the possibility of chipping or damaging the ledger plate.

With particular reference to Figure 3 it will be observed that the rear portion of the ledger plate 14 is provided between the spring arms 30 with a tool receiving recess 45 which partly extends over a socket 46 in the top of the guard and the rear wall of the socket 46 constitutes a fulcrum about which the screw driver or other convenient tool is rocked so as to elevate the ledger plate. By this means it is possible to remove the ledger plate without severing rivets or without removing bolts or the like.

The ledger plate may be conveniently clamped onto the guard and when applied is positively held against displacement, although capable of almost instant removal by the operator.

Having thus fully described the invention, what I claim is:—

1. A guard comprising a body having a cavity and having a bridge member spanning the cavity, and a ledger plate having a U-shaped incision defining a partly severed portion extended downwardly to define a spring finger adapted to be received in said cavity and securely engaged with said bridge member whereby to hold the ledger plate securely in position, said guard having a pair of shoulders and a socket between said shoulders and said ledger plate having a lip received in said socket and having a pair of shoulders flatly engaging said first named shoulders whereby to cooperate with said spring finger to hold the ledger plate securely in position.

2. A guard and ledger plate comprising a body having the rear portion thereof formed with a pair of recesses extending entirely therethrough, one wall of each recess being approximately V-shaped and having a central transverse enlargement, and a ledger plate having its rear portion formed with attaching spring arms adapted to be sprung

over the transverse enlargement in the walls of the recesses.

3. A guard and ledger plate comprising a body having the rear portion thereof formed with a pair of recesses extending entirely therethrough, one wall of each recess being approximately V-shaped and having a central transverse enlargement, a ledger plate having its rear portion formed with attaching spring arms adapted to be sprung over the transverse enlargement in the walls of the recesses, the said spring arms having their terminal portions extended outwardly and then inwardly to define hooks adapted for movement over the enlargements of said walls.

4. In a device of the character described, a guard having the rear portion thereof formed with recesses, one wall of each recess being approximately V-shaped in cross section, and a ledger plate having the rear portion formed with downwardly projecting spring arms to engage the said V-shaped walls of the recesses whereby to securely attach the rear portion of the ledger plate to the guard, the terminal portions of said spring arms being extended outwardly and then inwardly.

5. A guard and ledger plate comprising a body, having a pair of recesses extended entirely therethrough and one wall of each recess being approximately V-shaped in cross section, and a ledger plate having a pair of spring attaching arms adapted for clamping engagement with said V-shaped walls, said body being provided between said recesses with a socket, one wall of which constitutes a fulcrum for engagement by a lever employed in lifting the ledger plate, said body being provided with a pair of shoulders and said ledger plate being provided with a second pair of shoulders engaging said first named shoulders and with a lip confined between said first named shoulders.

6. A guard and ledger plate comprising a body having a cavity and having a bridge member spanning the cavity, a ledger plate having a U-shaped incision defining a partly severed portion extending downwardly to define a spring finger adapted to engage said bridge member whereby to hold the ledger plate against rearward movement, the rear portion of said ledger plate being provided with a pair of downwardly extending spring arms, the terminal portions of which are curved longitudinally, said body being provided with recesses having walls approximately V-shaped in cross section and flatly engaged by said spring fingers, said body being provided with a socket located adjacent the rear portion of the ledger plate, said socket being adapted for the reception of a lever.

JOHN PETER BAGAN.
